UNITED STATES PATENT OFFICE.

WILLIAM A. FREEMAN, OF HAMILTON, ONTARIO, CANADA, ASSIGNOR TO W. A. FREEMAN COMPANY, LIMITED, OF HAMILTON, ONTARIO, CANADA.

REFRIGERATED-DISPLAY-COUNTER TOP.

1,304,956.

Specification of Letters Patent. Patented May 27, 1919.

Application filed July 8, 1918. Serial No. 243,992.

To all whom it may concern:

Be it known that I, WILLIAM A. FREEMAN, a subject of the King of Great Britain, residing at Hamilton, in the county of Wentworth and Province of Ontario, Canada, have invented certain new and useful Improvements in Refrigerated-Display-Counter Tops, of which the following is a specification.

My invention relates to improvements in drippage disposal systems, and more particularly to a system for conveying drippage from the ammonia coils of refrigerated display counters, and consists essentially of drip gutters longitudinally disposed beneath the coils, together with concealed means within the coil supports for carrying the water from the gutters to a common discharge system beneath the counter top.

The invention has for its object to provide a drippage disposal system of the class specified which will effectively dispose of all moisture which collects on the exterior of refrigeration coils due to the warm surrounding atmosphere, without permitting it to drip upon the surface of the display counter slab, where it would mingle with the displayed goods.

A further object is attained in the provision of such a system which will be substantially concealed within the coil supports.

A still further object is to provide a device which will be simple, durable, efficient in operation, and inexpensive to manufacture.

These, together with other objects apparent to those skilled in the art, may be attained by the construction, combination and arrangement of the parts which will be hereinafter more fully described, illustrated in the accompanying drawings, and pointed out in the claims hereunto appended.

Reference being had to the accompanying drawing, Figure 1 is a side elevation of the device shown partly in section, Fig. 2 is a front elevation also shown partly in section on the line A—A in Fig. 1, and Fig. 3 is a top view of the portion of the bracket through which the drain passes.

Similar reference characters refer to similar parts throughout the several views.

In the drawing, A indicates the counter top slab, which is shown in a slightly forward sloping position. This is not a necessary factor, as some counter top slabs are

level, and this invention may be applied to the level type as well as the sloped. B indicates the supporting woodwork, which forms part of the counter proper. C designates a portion of one of the brackets which hold a front and top display glass. These hereabove described parts are old and hence form no part of the present invention.

The refrigerating coils D, which are horizontally disposed and run longitudinally of the counter, are supported by a transverse rib 2 integral with the supporting column E, and which is hollowed out to prevent lateral movement of said coils. The coils rest freely upon said rib and are permitted to longitudinally ride according to expansion and contraction due to change in temperature.

The said column extends to within a suitable distance above the coils and is provided with a threaded socket 3 which is adapted to receive a corresponding threaded portion of the upper part of the bracket C. The lower end part of the column is turned to form a round lug 4 which engages a corresponding pocket in a boss 5 formed on the bracket C. The upper surface of said boss is saucer shaped, and the shoulders of the column, which are formed by the lug 4, rest upon the bottom of the saucer, constituting a circumferential channel 6 therearound.

Drip gutters 7 disposed longitudinally directly beneath each coil D, to receive the moisture which drips therefrom, are supported by the edges of a pair of drainage channels 8, one on each side of and paralleling the coil supporting rib 2. These channels slope toward the center and communicate with a core 9 in the column E by means of ducts 10. The said drip gutters are formed with a double bottom providing a dead air insulation pocket 11 to eliminate condensation of moisture on the bottom.

The core 9 of the column E registers at the bottom with a passage 12 in the bracket C, which passage is tapped at its lower end to receive a tube 13 which serves the secondary purpose of a bolt, there being a nut 14 threaded thereon and tightened against the slab A securing the bracket C to the same.

To the lower end of the tube 13 is attached a pipe 15 which conveys the water to a common pan under the counter.

A certain amount of moisture or condensation will form upon the bottom of the

channels 7 and will follow the same by capillary attraction, to the column E from whence it will run to the circumferential channel 6 at the base of said column, and 5 thence through a pair of ducts 16 into the passage 12.

The upper end parts of the column E, above the coils D, are provided with lateral opposed bosses 17 tapped to receive threaded 10 ends of stay rods 18 which are likewise secured to the adjacent columns. The rods are for the purpose of securing the columns against lateral movement due to the expansion and contraction of the coils, which 15 would otherwise in time tend to loosen same from their keepers.

Having now fully described my invention, what I claim and desire to secure by Letters Patent of the United States, is:—

- 20 1. In a device of the class described, the combination with a counter top and glass holding bracket rigid with the counter top, of a cored column secured at its upper end to the top portion of the bracket and at its lower end to the bottom portion of the bracket, a horizontal transverse coil support integral with and at the upper end part of said column, a channel formed on each side of said coil support and communicating with the core of said column, horizontal drip gutters disposed directly beneath the coils and supported by the outer sides of said channels, the core of said column communicating at the lower end with a passage 25 extending below the counter top, substantially as set forth.
- 30 2. In a device of the class described, the combination with a counter top and glass holding bracket rigid with the counter top, of a cored column secured at its upper end to the top portion of the bracket and at its lower end to the bottom portion of the bracket, a horizontal transverse coil support integral with and at the upper end part of 35 said column, a channel formed on each side of said coil support and communicating with the core of said column, horizontal drip gutters disposed directly beneath the coils and supported by the outer sides of said channels, the core of said column communicating at the lower end with a passage 40 extending below the counter top, substantially as set forth.
- 40 3. In a device of the class described, the combination with a counter top and glass holding bracket rigid with the counter top, of a cored column secured at its upper end to the top portion of the bracket and at its lower end to the bottom portion of the bracket, a horizontal transverse coil support integral with and at the upper end part of 45 said column, a channel formed on each side of said coil support and communicating with the core of said column, horizontal drip gutters disposed directly beneath the coils and supported by the outer sides of said channels, said gutters being provided with a double bottom constituting an air pocket between, the core of said column communicating at the lower end with a passage extending 50 below the counter top, substantially as and for the purpose specified.
- 50 4. In a device of the class described, the combination with a counter top and glass holding bracket rigid with the counter top, of a cored column secured at its upper end to the top portion of the bracket and at its lower end to the bottom portion of the bracket, a horizontal transverse coil support integral with and at the upper end part of 55 said column, a channel formed on each side of said coil support and communicating with the core of said column, horizontal drip gutters disposed directly beneath the coils and supported by the outer sides of said channels, the core of said column registering at the lower end with a passage in the bottom portion of said bracket, a tube passing through said slab and threaded into said passage, a nut threaded on said tube and tightened against the under side of said slab, a pipe threaded on the lower end of said tube, as and for the purpose set forth.

formed in the bottom portion of said bracket, said portion of said bracket having a saucer shaped depression concentric with 65 said column and constituting an annular channel therearound, a horizontal transverse coil support integral with and at the upper end part of said column, a channel formed on each side of said coil support and communicating with the core of said column, horizontal drip gutters disposed directly beneath the coils and supported by the outer sides of said channels, the core of said column communicating at the lower end with 70 a passage extending below the counter top, ducts communicating with said annular channel and said passage, substantially as set forth:

4. In a device of the class described, the combination with a counter top and glass holding bracket rigid with the counter top, of a cored column secured at its upper end to the top portion of the bracket and at its lower end to the bottom portion of the bracket, a horizontal transverse coil support integral with and at the upper end part of 75 said column, a channel formed on each side of said coil support and communicating with the core of said column, horizontal drip gutters disposed directly beneath the coils and supported by the outer sides of said channels, the core of said column communicating at the lower end with a passage 80 extending below the counter top, stay rods secured at one end to said column and at the opposite end to the adjacent columns, as and for the purpose specified.

5. In a device of the class described, the combination with a counter top slab and glass holding bracket rigid with the slab, of a cored column secured at its upper end to the top portion of the bracket and at its lower end to the bottom portion of the bracket, a horizontal transverse coil support 85 integral with and at the upper end part of said column, a channel formed on each side of said support and communicating with the core of said column, horizontal drip gutters disposed directly beneath the coils and supported by the outer sides of said channels, the core of said column registering at the lower end with a passage in the bottom portion of said bracket, a tube passing through 90 said slab and threaded into said passage, a nut threaded on said tube and tightened against the under side of said slab, a pipe threaded on the lower end of said tube, as and for the purpose set forth.

In testimony whereof I have affixed my 120 signature.

WILLIAM A. FREEMAN.

Witness:

H. G. HENDRY.
